Primary Examiner — Ryan Harvey(74) *Attorney, Agent, or Firm* — Dunlap Bennett & Ludwig, PLLC; Brendan E. Squire(57) **CLAIM**

The ornamental design for a psoas massager, as shown and described.

DESCRIPTION

FIG. 1 is a perspective view of the psoas massager showing my new design.

FIG. 2 is a front elevation view of the torso massage device.

FIG. 3 is a back elevation view thereof.

FIG. 4 is a left elevation view thereof.

FIG. 5 is a right elevation view thereof.

FIG. 6 is a top plan view thereof.

FIG. 7 is a bottom plan view thereof.

FIG. 8 is a perspective view thereof in the expanded position; and,

FIG. 9 is an in use view thereof in the expanded position. The broken lines shown in the drawings illustrate portions of the psoas massager that form no part of the claimed design. The broken lines in FIG. 9 showing the psoas massager in use illustrates environment and forms no part of the claim.

1 Claim, 8 Drawing Sheets(56)
